United States Patent Office

Des. 178,640
Patented Sept. 4, 1956

178,640

DRESS

Rose N. Choolfain, Belmont, Mass.
Application May 9, 1956, Serial No. 41,422

Term of patent 3½ years

(Cl. D3—26)

F/G. 2

F/G. 1

Figure 1 is a front view of the dress.
Figure 2 is a rear view of the dress.

I claim:

The ornamental design for a dress, as shown.

References Cited in the file of this patent

UNITED STATES PATENTS

D. 133,319 Hoffmann ----- Aug. 4, 1942

OTHER REFERENCES

Montgomery Ward, Fall and Winter, 1955-1956, page
32, item E.